UNITED STATES PATENT OFFICE.

HENRY B. GROSS, OF PHILADELPHIA, PENNSYLVANIA, ASSIGNOR OF ONE-HALF TO BENJAMIN BROOKE, OF SAME PLACE.

SAFETY-POCKET.

SPECIFICATION forming part of Letters Patent No. 265,228, dated September 26, 1882.

Application filed May 23, 1882. (No model.)

To all whom it may concern:

Be it known that I, HENRY B. GROSS, a citizen of the United States, residing at Philadelphia, in the county of Philadelphia and State of Pennsylvania, have invented a new and useful Safety Watch-Pocket, of which the following is a specification.

My invention relates to an improvement in pockets for watches; and it consists of a loop, strap, band, or perforation placed at either side or end of the pocket. It must be large enough to pass a watch-chain, but too small for the passage of a watch, the object of the invention being to prevent the abstraction of the watch without the wearer's notice. I attain the object by the device set forth in the accompanying drawings, in which—

Figure 1 is a front view. Fig. 2 is a transverse view of a pocket and attachment. Fig. 3 is a top or edge view; and Fig. 4 is a view taken from within, the inner side of the pocket and vest being removed.

Similar letters refer to similar parts throughout the several views.

A is a vest, the pocket B of which has a stay-piece, C, composed of a loop, strap, or band, fixed to the inside, through which the bar or hook end of the watch-chain D is passed. The opening a must be large enough to freely pass and slide the chain, but not the accompanying watch E. Any effort to steal the watch would be detected by the out-hanging portion of the chain drawing through the opening.

I claim—

The combination, with a pocket, of a stay-piece, C, the same being attached at the top upon the inside of the pocket and provided with an opening, a, all being arranged substantially as shown and described.

HENRY B. GROSS.
